C. G. CARLSON

SHEET METAL RECEPTACLE

Filed Nov. 3, 1922

Clifford G Carlson
Inventor

By Clarence S. Walker.

His Attorney

UNITED STATES PATENT OFFICE.

CLIFFORD G. CARLSON, OF JAMESTOWN, NEW YORK.

SHEET-METAL RECEPTACLE.

Application filed November 3, 1922. Serial No. 598,905.

This invention relates to an improvement in a sheet metal receptacle and more particularly to a double wall insulated sheet metal receptacle intended to be used as a substitute for a cedar chest.

The use of a cedar chest has many advantages but it also is open to the objection that wood of the proper quality is not easy to obtain; that a cedar chest is not a protection against fire and that it is impossible to finish a cedar chest to match furniture.

The chief object of this invention is to provide a double wall insulated sheet metal chest having its compartment provided with means to exhale the odor of cedar and, therefore, adapted to be used for protecting clothing against moths and also against fire. Such a chest can be furthermore, used for the storage of other articles such as silverware and papers which in the ordinary home are not protected against danger of fire due to the expense of a safe.

A further object of this invention is to provide a sheet metal receptacle which is made up of parts which are secured together and yet are capable of a slight relative movement so that exposure to extreme heat will not cause it to warp out of shape. Furthermore, all parts of the chest made in accordance with this invention can be entirely grained by machine due to the fact that the side, end and bottom panels can be completely grained before they are combined with the other parts of the chest.

Another object of this invention is the process of making a chest which process comprises the following steps:

First. Insulation is poured into a temporary mold, the edges of which are formed by the edge strips of the chest.

Second. After the insulation has set, the temporary forms are removed and the insulation is exposed to the air so that the surplus moisture will evaporate, in order to hasten this step heat may be applied.

Following this, the outer panels and inner lining are secured to the edge strips, thus forming a double wall insulated receptacle in which there is no danger of dampness due to the condition of the insulation.

Other objects will appear upon examination of the following description taken in connection with the annexed drawing which forms a part thereof and in which

Fig. 1 is a plan view of a chest embodying this invention.

Fig. 2 is a side elevation of such chest.

Fig. 3 is a horizontal cross section taken along the lines 3—3 of Fig. 2.

Fig. 4 is a transverse cross section taken along the lines 4—4 of Figs. 1 and 2.

Fig. 5 is an enlarged detail showing the manner in which the panels are secured to the edge strips.

Fig. 6 is an enlarged cross section of the top of the box showing the manner in which the cover is mounted on the side walls.

Figs. 7 and 8 are detailed views illustrating the joining portions of the panels and edge strips; and

Fig. 9 is an enlarged view of one of the edge strips and insulation before the panels are applied.

Referring to the drawings, the numeral 10 is used to designate the chest embodying this invention. This chest comprises the edge strips 11, side panels 12, end panels 13, bottom panels 14, insulation 15, and cover 16.

The edge strips 11 are preferably made of channel form, such as is shown particularly in Fig. 5, both lateral edges of the bottom and side strips being provided with the flanges 17 which are folded back to form pockets 18. In the flanges 17 are a plurality of slots 19 for the purpose to be described later.

The side, bottom and end panels are of the same general construction differing merely in dimensions and for that reason only the side and end panels shown in Fig. 5 will be described in detail. These panels are provided with flanges 20 along each edge which are made of sufficient depth to enter the pockets 18 in the edge strips. Stamped from the flanges 20 are tongues 21 suitably spaced so that when the flanges are assembled with the edge strips the tongues will enter the slots 19, thus preventing the removal of the panels after they are once in place without, however, preventing a certain weave between the panels and edge strips, which may result from the exposure of the chest to fire or other conditions.

The upper edge strips 11 which for convenience will hereafter be referred to by the numeral 22, differ from the other edge strips previously described in formation by reason of the provision of pockets 18 along one lateral edge only. The other lateral edge, 110

which is adjacent the cover 16, is provided with a flange 23 bent at right angles to the flat portion 24.

The inner wall or lining of the chest preferably consists of a metal strip 25 which forms the sides and bottom of the compartment and two sheets 26 which form the ends. Referring to Fig. 3, it will be noted that the side edges of the strip 25 are flanged and that the sheets 26 rest against these flanges. These sheets 26 are preferably welded to the flanges 27 of the strip 25 but it is obvious that other means for connecting parts of the lining may be employed if desired. The upper edge of the side lining 25 at the rear of the box is bent at right angles to form the horizontal portion 28 and again at right angles to form the flange 29. This flange 29 bears directly against the portion 24 of the edge strip and the parts are preferably assembled by means of screws 30.

The upper edges of the end lining plates 26 and the upper edge of the strip 25 are formed in a similar manner with the exception that the horizontal portion 31 is made shorter than the portion 28. The vertical part 32, however, corresponds exactly to the part 29. When the linings are assembled in the chest it will be noted that between the parts 32 and the portions 24 are formed pockets 33 in which are placed strips of packing 34. The screws 35 by which the linings are secured to the edge strips pass through this packing. At suitable intervals in the lining walls are provided openings 36 by which the screws may be reached and operated.

The cover 16 comprises an outer panel 37 having a short flange 38 along the rear side and longer flanges 39 along the ends and other side. The lining 40 of the cover is flanged at 41 and suitably secured to the outer panel 37, the flanges 41 resting against the flanges 38 and 39 so as to prevent the entrance of any moisture between the parts. Resting on the portions 28 and 31 are strips 42 of asbestos which also act to prevent the entrance of any moisture between the cover and side walls and which, in addition, deaden the sound, and make the compartment air tight to protect the contents. The flanges 39 of the cover enter the pockets 33 and rest against the packing 34, thus providing a further seal. Any suitable form of hinge 43 may be provided. Imbedded in the cover and projecting from the lower rear edge of the cover are pins 47. Apertures in the lining 25 admit these pins when the cover is closed so as to prevent an unauthorized lifting of the cover by removing the hinge pins. The pins 47 and the lock hold the cover so that it can only be raised by releasing the lock.

In order to give the cedar odor, which is necessary to protect garments, a cedar board

48 is placed in the bottom of the chest. If desired, however, cedar shavings may be inserted behind the lining of the cover, or chest, and allowed to permeate the interior through vents, or holes, formed in the lining. It is also possible to provide a small box containing cedar oil which can be put in one corner of the compartment and which would provide the necessary odor.

Any suitable form of lock 49 may be used, the particular one here shown, is of the tumbler type. Projections from the top are avoided by imbedding the handles 50 in the depressions 51 in the upper panel 37. In order to permit of the easy moving of chest, casters 52 are secured to the bottom.

In making the chest the edge strips 11 are first rigidly secured together to form a skeleton frame-work; suitable inner and outer forms are now mounted between the strips and the insulation poured into the mold so formed and allowed to harden. After this has taken place, the temporary inner and outer forms are removed and the excess moisture from the insulation permitted to evaporate by exposure to the air or heat may be applied to hasten the evaporation. This step in the process avoids one of the greatest objections to the use of insulation of this kind in a double wall receptacle, since unless the excess moisture is allowed to evaporate it will in time permeate the walls and will not only cause the metal to corrode but will also discolor the outer walls and make the inner walls damp.

The outer faces of the edge strips are now grained, in any desired manner, by machinery and at the same time the side, end and bottom panels are also grained by machinery, a step formerly impossible in a chest having depressed panels, which could only be grained by hand. After being previously grained, the panels are slipped into place, the tongues 21 entering the slots 19 and preventing their removal. It will, however, be noted that the flanges of the panels do not completely fill the pockets 18 so that a certain amount of relative movement between the panels and edge strips are permitted.

By reason of the construction above disclosed it is obvious that the connection between the panels and edge strips will prevent the parts from separating but will also permit warpage of certain parts without warpage of the entire chest, thus overcoming the great objection to the usual form of double wall chest in which the entire outer wall is formed into a single unit.

The insulating material is preferably of monolithic form consisting of a mixture of calcium sulphate (plaster of Paris) and asbestos fibre in the ratio of 70 per cent and 30 per cent, respectively. In place of this insulation, however, successive layers of as-

bestos paper may be employed. These layers are assembled with the edge strips in a manner similar to that described above before the side panels are inserted, or the panels could be assembled first and asbestos inserted.

The cover 16 is formed by packing the insulation into the formed lining 40 allowing it to set and allowing the excess moisture to evaporate before securing the outer panel 37. If desired, layers of asbestos paper may be used instead. The joinder of the lining to the outer walls around the cover opening will permit considerable warpage before the cover is thrown out of alignment so that it will not fully seal the box.

While this chest has been described as having a cover at the top, where it is least exposed to fire and least subjected to the influences of climatic changes, it is, of course, obvious that the cover could be made on the side or end if desired. Moreover the cedar board 48, or other means for exhaling the odor of cedar, is not essential to this invention and would be removed if the chest were to be used merely for a household safe.

It is understood, however, that while the applicant has shown and described one embodiment of this invention, he is not to be limited thereto since others may be made without departing from the spirit and scope of the invention as set forth in the following claims.

Having thus set forth my invention which I claim as new and for which I desire the protection of Letters Patent is—

1. A sheet metal double walled receptacle

comprising edge strips rigidly joined together to form the frame work, said strips having reversed flanges forming pockets along the sides and a plurality of slots in said flanges, and panels having flanges which enter said pockets, the latter flanges being slotted to provide tongues which enter the slots in the strip flanges and prevent separation of panels and strips.

2. A sheet metal double walled receptacle comprising edge strips, panels secured to said strips, to form the outer wall, a lining forming the inner wall removably secured to the upper edge strips, packing inserted along the inner side of the end strips and one side strip to separate them from said lining and provide pockets therebetween, a cover hinged to the upper edge strip and having flanges which enter said pockets when the cover is closed and rest on said packing.

3. The process of making an insulated sheet metal receptacle having edge strips and side, end and bottom panels, consisting in first assembling the insulation with the edge strips and second securing the panels to said edge strips.

4. The process of making an insulated sheet metal receptacle consisting in casting the insulation in the edge strips of the receptacle, allowing the moisture to evaporate from said insulation and then securing the side, end, and bottom panels to said edge strips.

In testimony whereof I have affixed my signature.

CLIFFORD G. CARLSON.
